CLINTON S. BURNS, OF KANSAS CITY, MISSOURI.

FLUSHING DEVICE.

1,130,885.

Specification of Letters Patent.

Patented Mar. 9, 1915.

Application filed May 11, 1914. Serial No. 837,734.

To all whom it may concern:

Be it known that I, CLINTON S. BURNS, a citizen of the United States, residing at Kansas City, in the county of Jackson and 5 State of Missouri, have invented certain new and useful Improvements in Flushing Devices; and I do declare the following to be a full, clear, and exact description of the invention, such as will enable others skilled 10 in the art to which it appertains to make and use the same, reference being had to the accompanying drawings, and to the letters and figures of reference marked thereon, which form a part of this specification.

15 My invention relates to flushing devices for railway toilets, and has for its principal object to provide a device of this character, which may be operated only when a coach carrying the device is traveling at a predetermined speed, in order to prevent flushing 20 the toilet while the train is standing at a station platform, or while running slowly through the yards. In accomplishing this object, I have provided improved details of 25 structure, the preferred forms of which are illustrated in the accompanying drawings, wherein—

Figure I is a side elevation of a portion of a coach equipped with a toilet flushing 30 device embodying my invention. Fig. II is an enlarged view of the operating mechanism, shown in its relation to the car wheel; one of the side keeper disks being removed in order to show the governor mechanism.

35 Fig. III is a transverse section of the operating disk. Fig. IV is an enlarged perspective view of the operating disk and governor mechanism; the front disk being removed for better illustration.

40 Referring more in detail to the drawings:—1 designates a railway coach of ordinary construction, having a toilet 2 that is provided with the usual valve mechanism (not shown), and a pull lever 3 for operating 45 the said valve mechanism.

50 Fixed to the under side of the coach floor is a depending bracket 4 and pivotally mounted on the bracket and extending longitudinally of the coach and over one of the 55 car wheels or other traveling member of the car, are spaced beams 6, having a push-rod 7 connected with their free ends and extending upwardly through the floor of the coach adjacent the toilet. The portion of the rod 7 above the floor carries a collar 9 and the part of the rod between said collar 9 and

the car floor is surrounded by a coil spring 10, whereby the rod 7 and beam 6 are yieldingly held in their normal, elevated position above the car wheel or actuating member. 60

The push-rod 7 is preferably connected to the beams 6 by means of a coil spring 11, which surrounds the lower end of rod 7 and is connected thereto and to the beams 6, so that on pushing rod 7 downwardly the operating mechanism, which is presently described, will be brought in yieldable engagement with the car wheel. 65

70 Revolubly mounted on an axle 12, which is projected between the beams 6 and mounted therein, is a clutch 14 comprising side keeper disks 15 which are secured together by a spacer 16 of small diameter; the disks 15 being of such size that their peripheries are normally adjacent and adapted for contacting the rim of the car wheel when thrown into operative position by rod 7. On the inner side of and near the periphery of each keeper disk 15, is an inturned, annular flange 18, and slidably mounted between the 75 disks and held within the said flanges 18 is a floating ring 19, having a peripheral flange 20 extending outwardly between the disk flanges 19 and provided with a peripheral groove 21. Secured to the ring flange 20 80 and adapted for travel in the groove 21 is a cord 22, which is passed over a pulley wheel 23 that is mounted in the bracket 4, and thence upwardly through the car floor to the pull-lever 3 with which it is connected. 85

90 Projecting between the disks 15 adjacent the spacer 16 are pins 24, and pivotally mounted on said pins and suspended therefrom on opposite sides of the spacer, are 95 governor arms 25 of such length that their free ends normally lie within the floating ring and out of contact with clutch bosses 26 on the inner face of the ring.

99 Each of the arms 25 carries a weight 27, which is slidably mounted on the arm and provided with a set screw 28 adapted for projection into one of the several sockets 29 in the arm to fix the weight in an adjusted position and thereby determine at what speed of travel of the train the toilet may 100 be operated.

105 Each of the arms 25 is connected with the spacer 16 by a spring 30, which yieldingly retains the arm in close relation to the spacer and resists the centrifugal force that tends 110 to throw the arms outwardly into locking engagement with the floating ring.

With the mechanism described, when the beam 6, upon which the clutch disks are mounted, is lowered so that the disks will contact with a car wheel or axle, or other moving part of the car, frictional engagement of the disks with the moving part will carry the disks around on their axles and centrifugal force generated by rotation of the disks will throw the governor arms outwardly against the tension of their retaining springs until one of the arms lodges back of its clutch boss 26 and thereby locks the friction disks to the floating ring, which is carried therein. When the parts are locked, the ring rotates with the disks and the cord 22 is wound in the peripheral groove of the floating ring, so that the lever 3 is pulled downwardly and the toilet flushed. It is apparent, however, that if the clutch mechanism were lowered while the car were standing or traveling at such slow speed that sufficient centrifugal force would not be generated to spread the governor arms, the flushing would not take place, and in order to insure flushing as soon as the car has started and gained sufficient speed to operate the clutch, I have provided a latch mechanism which I will now describe.

Pivottally suspended from the floor of the car is an arm 31, which is connected with the push rod 7 by a spring 32, so that the arm is normally yieldingly tensioned toward the rod, and fixed on said rod is a stop-collar 33, which is adapted for engagement by the free end of the stop-arm 31 when the arm is pulled inwardly by the spring 32. The spring 32 is so arranged relative to the push-rod and arm 31, that when the rod is in normal or elevated position the spring is inert, but that as soon as the rod is forced downwardly, the spring is tensioned and tends to pull the stop-arm inwardly, so that it will engage the stop-collar and prevent upward movement of the push rod. It is apparent that with this construction, when the push rod is forced downwardly the stop-arm will engage the collar and hold the push rod against upward movement, thereby insuring engagement of the friction disk with the car wheel or other moving part.

Connecting the stop-arm 31 with the floating ring 19 is a cord 34, which is so arranged relative to the stop-arm and ring that it is ordinarily slack, but so that when the floating ring is revolved sufficiently, the cord will be straightened and the stop-arm pulled out of the path of the stop-collar and the push-rod allowed to return to its initial position under tension of its spring.

The operation of the device while the car is in motion has heretofore been described. In the event, however, that the apparatus should be operated while the car was standing or traveling at a low speed, the friction

disk would be moved into engagement with the actuating part of the car, but the disk would either not be revolved at all, or it would be revolved at such a low speed that the governor arms would not be thrown into engagement with the bosses on the floating ring and the flushing apparatus would not be actuated. In order, however, to secure actuation following the lowering of the push-rod I have provided the latch mechanism just described. It is apparent that with this mechanism, when the car is standing or traveling slowly, the rod when lowered will pull the stop-arm over into contact with the collar, so that the arm is held depressed and the friction disk in engagement with its actuating part. The mechanism remains in this condition until the car has attained the predetermined actuating speed, when the proper governor arm engages the floating ring and revolves the ring to tension the cord 22, so that it may pull the flushing lever and at the same time pull the cord 34 to release the push-rod. The toilet is then flushed and the rod returned to initial position for successive actuation.

By providing the floating ring with the two bosses and the separate governor arms on opposite sides of the center of the ring and arranging the pull cords as described, the device is adapted for actuation when the car upon which it is carried is moving in either direction, so that it is unnecessary to adjust the apparatus or duplicate the same.

Having thus described my invention, what I claim as new therein, and desire to secure by Letters-Patent, is:

1. The combination with relatively movable members, of a toilet bowl mounted on one of the members and comprising flushing mechanism, means operable from the other member for actuating the flushing mechanism, and manually operable means for establishing coöperation between the actuating mechanism and said other member.

2. The combination with relatively movable members, of a closet bowl mounted on one of the members and comprising flushing mechanism, means operable from the other member for actuating the flushing mechanism, and comprising a governor whereby actuation of the flushing mechanism is determined by the speed of travel of the relatively movable parts, and manually operable means for establishing coöperation between the actuating mechanism and said other member.

3. The combination with a railway car comprising running gear, of a closet bowl, normally inert flushing mechanism adapted for actuation from the running gear, and means for moving said mechanism into co-operative relation with the running gear.

4. The combination with a railway car,

comprising running gear, of a closet bowl, flushing mechanism including a clutch member adapted for actuation from the running gear of the car, and means for controlling 5 engagement of the clutch member with said running gear.

5. The combination with a railway car comprising running gear, of a closet bowl, flushing mechanism including a clutch member 10 adapted for operative engagement with the running gear, means for yieldingly retaining said clutch member out of its driving engagement, and means for moving said clutch into engagement with the running 15 gear against the tension of said yielding means.

6. The combination with a railway car, of a closet bowl comprising flushing mechanism, adapted for actuation from the running gear when the car is moving at a predetermined speed, and manual means for establishing co-operation between the flushing mechanism and the running gear.

7. The combination with a railway car, of a closet bowl, flushing mechanism including a clutch, and means whereby the mechanism is actuated when the clutch is moved at a predetermined speed.

8. The combination with a railway car, comprising running gear, of a closet bowl, flushing mechanism, a clutch adapted for actuation from the running gear, and governor mechanism in said clutch adapted for actuating the flushing mechanism when the 35 running gear travels at a predetermined speed.

9. In a flushing device for railway toilets, valve actuating mechanism, a normally independent actuating member, a clutch operable 40 from the normally independent member and comprising governor mechanism, and a setting device for establishing co-operation between the clutch and independent member.

45 10. In a flushing device for railway toilets, valve actuating mechanism, a normally independent actuating member, a clutch operable from the normally independent member and comprising governor mechanism, a setting device for establishing co-operation between the clutch and independent member, and a latch for maintaining 50 cooperative relation between the clutch and independent member.

55 11. In a flushing device for railway toilets, valve actuating mechanism, a normally independent actuating member, a clutch operable from the normally independent member and comprising governor mechanism, a setting device for establishing co-operation between the clutch and independent member, a latch for maintaining 60 cooperative relation between the clutch and independent member, and means operable 65 from the clutch for releasing said latch.

12. A flushing device for railway toilets comprising valve actuating mechanism, a clutch adapted for operative engagement with running gear and comprising a governor mechanism and a normally loose member adapted for actuation from the governor mechanism, and connection between the normally loose member and the valve actuating mechanism. 70

13. A flushing device for railway toilets comprising valve actuating mechanism, a clutch member comprising governor mechanism and a normally loose member adapted for actuation from the governor mechanism, and having operative connection with the 80 valve actuating mechanism, a setting device for moving the clutch to operative position, a latch for retaining the setting device in set position, and connection between the latch and the normally loose clutch member, 85 for the purpose set forth.

14. A flushing device for railway toilets comprising valve actuating mechanism, a clutch member comprising a revolute body provided with governor mechanism and a 90 normally loose member adapted for engagement by the governor mechanism, connection between the normally loose member and the valve actuating mechanism, means for setting the clutch, a latch for holding the 95 setting means in operative position, yielding means for moving the latch to setting position, and connecting between the latch and normally loose member for withdrawing the former from engagement with the 100 setting means.

15. A flushing device for railway toilets comprising valve actuating mechanism, a clutch comprising a hub and spaced disks mounted on the hub and provided with facing flanges, a floating ring confined within the disk flanges and provided with bosses, governor arms pivotally mounted on the clutch within the floating ring and adapted 105 for engagement with the ring bosses, means for moving the clutch into operative engagement with the normally independent member, whereby the clutch may be revolved, and connection between the floating ring and the valve actuating mechanism. 110

16. A flushing device for railway toilets comprising valve actuating mechanism, a clutch comprising a hub and spaced disks mounted on the hub and provided with spaced and facing flanges, a floating ring mounted within the flanges and having a peripheral flange located between the disk flanges, and having a boss on its inner face, a pin on said disks, a governor arm pivotally mounted on said pin, a spring for retaining the governor arm in inert relation to the ring boss, connection between the ring and valve actuating mechanism, and means for moving the clutch to operative 120 position. 125

17. A flushing device for railway toilets comprising valve actuating mechanism, a clutch comprising a hub and spaced disks mounted on the hub and provided with spaced and facing flanges, a floating ring mounted within the flanges and having a peripheral flange located between the disk flanges, and having a boss on its inner face, a pin on one of said disks, a governor arm 10 pivotally mounted on said pin, a spring for retaining the governor arm in inert relation to the ring boss, connection between the ring and valve actuating mechanism, means for moving the clutch to operative position, and a latch for retaining the clutch in operative position until the ring is actuated from the governor arm.
18. In a flushing device for railway toilets, valve actuating mechanism, a clutch member, a pivotal support, a clutch revolvably mounted on the pivotal support and comprising governor mechanism and a floating member adapted for actuation from the governor mechanism, connection between the floating member and valve actuating mechanism, a setting device connected with the pivotal support, a latch adapted for

retaining the setting device in operative position, and connection between the latch and floating member, whereby the setting device is released when the floating member is actuated.

19. In a flushing device for railway toilets, valve actuating mechanism, a pivotal support, a clutch member mounted on the support and comprising governor mechanism and a floating member, connection between the floating member and valve actuating mechanism, a push-rod connected with the pivotal support, yielding means for retaining the push-rod in initial position, a stop on said rod, a latch, a spring connecting the rod and latch to draw the latch to position for engaging the collar when the rod is depressed, and connection between the latch and floating clutch member, for the purpose set forth.

In testimony whereof I affix my signature in presence of two witnesses.
